United States Patent Office

Des. 203,191
Patented Dec. 14, 1965

203,191

URN

Michael M. Kaplan, 175 Central Ave., Passaic, N.J.

Filed Apr. 7, 1965, Ser. No. 84,659

Term of patent 14 years

(Cl. D29—28)

FIG. 1 is a front elevational view of an urn embodying my new design with the cover member in place;

FIG. 2 is an elevational view similar to FIG. 1 but from a different angle;

FIG. 3 is an enlarged top plan view;

FIG. 4 is an elevational view of the urn with the cover member positioned and fitted on the urn as a base;

FIG. 5 is a detailed cross sectional view taken on the line 5-5 of FIG. 1;

FIG. 6 is a detailed cross sectional view taken on the line 6-6 of FIG. 2;

FIG. 7 is a detailed cross sectional view taken on the line 7-7 of FIG. 1; and

FIG. 8 is a detailed cross sectional view taken on the line 8-8 of FIG. 3.

I claim:

The ornamental design for an urn, substantially as shown.
